DIRECTION FINDER ANTENNA SYSTEM

Edward J. Hefele, Amityville, N. Y.

Application April 27, 1937, Serial No. 139,143

16 Claims. (Cl. 250—11)

This invention relates to direction finders and more particularly relates to antenna systems for right-left indicating direction finder systems.

Automatic right-left indicator systems, particularly for aircraft, have heretofore generally depended upon the formation of cardioid reception patterns and used a loop antenna combined with a vertical or non-directional antenna in a predetermined relation. The resultant cardioid patterns depended upon critical tuning and electrical phasing of the loop antenna system. Changes in temperature of the loop antenna and slight variations in tuning caused serious misphasing at the antenna stage of the radio receiver and resulted in reception patterns producing null or zero intensity on bearings actually many degrees off-course. Such directional errors are very serious, particularly on aircraft where radio directional guidance is often the sole navigational aid.

In accordance with my present invention, I contemplate producing cardioid reception patterns by means of vertical antenna arrays combined at the antenna input stage in a predetermined manner. The cardioid patterns of my invention are not dependent upon tuning or critical variable electrical conditions but remain constant after installation for all reception purposes. I utilize the vertical antenna array to produce the alternate right and left cardioid reception patterns for controlling the deflections of a right and left indicator.

Vertical mast antennae, even when streamlined, produces an aerodynamic resistance or drag to flight of approximately six pounds at a flight speed of 200 miles per hour. Accordingly, it is greatly advantageous to minimize the number of mast antennae arrays necessary for accurate directional guidance. In accordance with my invention, two, three or four vertical antennae may be used for such a right-left indicator.

An aircraft traveling at high speed through the atmosphere often passes through rain, dust, snow and fog, the particles of which impinge at high velocity upon the antenna structure and set up static impulses which are transmitted through to the radio receiver. Such static often seriously impairs reception. Loop antennae have been successfully shielded by enclosing them in a metallic housing, which housing is placed at 45 grounded potential at its nodal point. In accordance with my invention, I provide a metallic shield surrounding the mast antenna and connect the shield to ground potential through a radio frequency choke coil. In this manner, the 50

charges produced by the impinging high velocity particles are dissipated by conduction to ground through the high impedance choke coil and the radio signals are only somewhat reduced in 5 intensity as they pass through the shield to the enclosed mast antenna. By maintaining the shield at a high radio frequency impedance, the sensitivity of reception by my novel shielded mast antenna is substantially maintained. A preferred construction for an anti-static antenna 10 is the use of a doublet or opposed mast antenna array, each mast being surrounded by a spaced shield connected to ground by an individual choke coil. All electrical impulses and transients 15 are conducted to ground free of any part of the radio circuit.

Accordingly, it is an object of my present invention to provide a novel method of and means for producing directional reception patterns with 20 vertical antennae.

Another object of my present invention is to provide a novel right-left indicating radio directional system having directional characteristics independent of tuning or electrically varying 25 conditions.

A further object of my present invention is to provide a novel anti-static vertical antenna system.

These and other objects of my present invention 30 will become apparent in the following description of the invention taken in connection with the drawings, in which:

Figures 1 and 1A are schematic showings of preferred non-directional antennae enclosed by 35 streamlined shields for eliminating static electrical pulses encountered in high speed flight.

Figure 2 is an enlarged cross-sectional view taken along 2—2 through the anti-static mast antenna of Figure 1.

Figure 3 is a fragmentary elevational view of 40 a modified shield for the anti-static mast antenna of my present invention.

Figure 4 is a cross-sectional view taken along 4—4 of Figure 3.

Figure 5 is a schematic electrical diagram of 45 a right-left indicator operating with a double cardioid produced by two vertical antennae.

Figures 6 to 15 illustrate different opposed 50 vertical antenna arrangements combined to produce various directional reception patterns and are presented to aid in the description of my present invention.

Figure 16 is a schematic electrical diagram of 55 a modification of a right-left indicator corre-

sponding to Figure 5 and employing balanced doublet antenna arrays.

Figure 17 is a polar diagram of the right and left cardioid reception patterns produced by the antenna system of Fig. 16.

Figures 18 to 22 illustrate different forms of radio frequency time-delay networks which may be employed in carrying out certain modifications of my present invention.

Figures 23 is a schematic diagram corresponding to Figures 5 and 16 showing a preferred time-delay network in circuit with the antenna system.

Figure 24 is a schematic electrical diagram of a cardioid pattern right-left indicator in accordance with my present invention employing four vertical antenna arrays using mechanical switching.

Figure 25 is a schematic electrical diagram of a cardioid pattern right-left indicator in accordance with my present invention employing three vertical antenna arrays using mechanical switching.

Figure 26 is a schematic electrical diagram of a right-left indicator corresponding to Figure 25 but employing electronic switching means at the antenna input and indicator.

In Figure 1 I have shown in elevation a preferred arrangement for shielding the vertical antenna from the effects of static produced by high velocity particles encountered in high speed flight through fog, dust and storms. The vertical or mast antenna array 30 is supported upon the exterior surface 31 of a vehicle such as a ship, car or aircraft. Figure 2 is a cross-section taken along 2-2 of Figure 1 and drawn to a larger scale. Although I prefer to illustrate the anti-static shielding as applied to a vertical mast antenna, it is to be understood that it may similarly be applied to the top and bottom rods of a doublet antenna array as well as to an antenna wire supported in any other angular relation with respect to the surface of the vehicle. In my co-pending application Serial No. 139,142 filed April 27, 1937, I illustrate a trailing wire antenna of an aircraft statically shielded by the principle herein described for the vertical mast.

The vertical antenna array 30 comprises a central conductor rod 32 which is the antenna wire for the radio receiver. Surrounding the antenna wire 32 is a metallic shield 33 preferably shaped in a tear-drop or stream line form having a minimum aerodynamic resistance in the direction of flight of the aircraft. Accordingly, the leading edge 34 of the shield 33 is wide and rounded and the trailing edge 35 is narrow and pointed. I prefer to incorporate a solid insulation material 36 between the conductor 34 and the metallic shield 33 and employ the insulation 36 to rigidly support the relatively thin and weak shielding 33 about the mast structure 30. I prefer to use a rubber composition which is moldable and accordingly will grip the corrugations 37 formed on the inner surface of the metal shield 33 to hold the latter in place. Gas-expanded rubber which is of light weight and composed of a multitude of gas cells forming a cellular structure is an excellent material for this purpose. Such rubber material generally known as "Rubatex" is readily moldable before final curing and can be incorporated between the shield 33 and the antenna wire 32 to hold the structure in a rigidly assembled and insulatingly spaced relation. The assembled streamlined structure 30 is insulatingly secured to a rigid base 29 which is fed into a socket 28 attached to

the vehicle structure 31. The bottom edge 33' of the shield 33 is spaced from the base 29 to prevent grounding of the shield except through the high radio frequency impedance to be described.

The trailing edge 35-35 is not joined but is kept open in order to reduce the eddy-currents generated in the conductor 33. The conductor 33 is preferably of copper or aluminum material.

10 The conductor 33 is connected to ground potential through a radio frequency choke 37 by connection leads 38. The rod or antenna wire 32 is connected to the primary 40 of the antenna stage coupling transformer 41 by connection lead 42. The secondary 43 of the antenna transformer 41 is tuned by a variable condenser 44, the output of which is connected to the radio frequency amplifier 45. The reception by the vertical rod 32 is similar to that of any corresponding non-directional mast antenna for use at the radio receiver 45 for communication or directional reception.

15 The high velocity atmospheric particles impinging on the antenna wire 33 dissipate their electrical charges therein which electrical charges are conducted to ground through the radio frequency choke coil 37. Once the electrical charges are dissipated in the shield 33 and conducted to ground, the shield performs the neutralizing action on the electrically charged particles.

20 The radio frequency signals pass through the shield 33 to the antenna rod 32 losing only a small amount of its energy due to the high radio frequency impedance of the shield 33 with respect to ground potential. The trailing edges 35 of the shield 33 minimizes any current losses induced in the shield by the radio frequency signal waves to increase the resultant shielding efficiency and increase the signal-to-static reception ratio by

25 the antenna system. I prefer to make the radio frequency inductance of the primary 40 of the antenna transformer 41 of lower impedance value than the corresponding radio frequency impedance of the radio frequency choke coil 37 connected to the shield 33. By maintaining such

30 relative impedance ratio, namely maintaining the shield at a higher impedance with respect to the antenna 32, the degree of signal absorption by the shield 33 is further diminished.

35 To further increase the efficiency of the shield by minimizing eddy-current losses therein, the shield is slotted transversely with slots 46 as shown in Figure 3. Reduction of the eddy-current losses is accomplished by reducing the mean

40 free electrical path in which any of the eddy-currents can flow and is performed by slotting the shield at different portions thereof. The slots 46 divide the shield into a corresponding plurality of segments 47. The segments 47 are electrically interconnected and the connections shown at 48 serve this function.

45 To assist in the gripping action of the segments 47 of the shield upon the molded insulation core 36, I prefer to crimp the slotted edges at regions 46 inwardly to form the crimped edges 48 for the shield segments 47. Figure 4 is an enlarged cross-sectional view taken along 4-4 of Figure 3 illustrating the preferred arrangement whereby the crimped edges 48 at the slotted portions are set into the molded insulation material 36 and rigidly maintain the shielded structure in place.

50 In Figure 1A I illustrate a modification of the simpler antistatic non-directional antenna repre-

sented in Figure 1. This system comprises two opposed antenna masts 20 and 21 forming a non-directional antenna. When the masts 20 and 21 are opposed and are of equal length they form a doublet antenna as is well known. This modification is independent of the relative lengths or positions of the masts 20 and 21. Each of the masts 20 and 21 are enclosed by a metallic shield 22 and 23 respectively. Shields 22 and 23 are similar to the hereinabove described shield structure 33 enclosing antenna 32 of Figure 1. The anti-static shields 22 and 23 are conductively connected to ground by their respective radio frequency choke coils 24 and 25.

The masts 20 and 21 are connected to the coupling coil winding 26. The center tap 27 of winding 26 is connected to ground potential. Antennae 20 and 21 form an effective non-directional doublet the electrical neutral point 27 of which is connected to ground potential. The winding 26 may be replaced by a transmission line to the radio frequency amplifier 28 at a remote point. A tuned circuit 29 is shown coupled to the winding 26 for selectively impressing radio signals induced in the antennae 20-21 on the radio frequency amplifier 28.

The non-directional antenna systems of Figures 1 and 1A may be employed for ordinary radio communication upon an aircraft or may be used as the non-directional antenna of a direction finding system. The metallic shields 22 and 23 conduct the changes of static electricity built up by the speed of the aircraft through rain, fog, dust and the like, to ground. The electrical impulses are neutralized with respect to the antenna array 20-21 since the nodal or neutral point of the antenna is connected to ground. It is to be understood that the antenna array 20-21 is mechanically supported upon the aircraft. The antenna array 20-21 may be supported in a vertical position or any other position with respect to the aircraft such as a horizontal position. The system of Figure 1A is adapted to eliminate any static pulses to an even greater degree than the single mast modification of Figure 1.

Figure 5 is a schematic illustration of a right-left indicating radio direction finding system of one modification of my present system. This system utilizes a cardioid reception pattern produced by two spaced mast antennae 50 and 51. The masts 50 and 51 are anti-statically shielded by the conductive shields 52 and 53 individually closing the antennae and connected to ground through the radio frequency choke coils 54 and 55 in a manner similar to the shielded antenna hereinabove described in connection with Figures 1 to 4. The size and spacing of the antennae 50 and 51 depend upon the type of vehicle or station it is installed upon and the frequency range it is operated upon. The antennae 50 and 51 are conducted by leads 56 and 57 to an intermediate position where the signals are combined in accordance with my present invention to produce the right and left cardioid reception patterns.

A time-delay network 58 is connected in series between either antennae 50 or 51 and the primary 60 of the radio frequency coupling coil 61, the secondary 62 of which is connected to the input of the radio receiver 63. The switching arrangement 64 to 67 indicates a mechanical switching system which alternately connects between contacts shown in the solid and dotted drawn position to correspondingly produce cardioid reception patterns having null positions to the right

and to the left. The output of the radio receiver is correspondingly successively switched to the right and left sections of a differentially connected indicating meter 68 by switch 69 operating in synchronism with the switching system 64 to 67. The theory of the operation of my present invention may be better understood by the following description in connection with Figures 6 to 23:

10 In Figure 6 I illustrate the central summation of signals from two spaced vertical antennae 50 and 51. The antenna coupling transformer 61 is connected at the mid-position of connection leads 56 and 57. The primary 60 of the transformer 61 has its mid-point connected to ground. The secondary 62 of the transformer 61 is connected to the input of the radio receiver 63. Figure 7 illustrates the polar reception pattern of the centrally summated spaced antenna system of 50-51. The polar ordinate at the angle θ indicates the relative intensity of the output of the antenna array of Figure 6 in correspondence with the angle of incidence θ of the radio signals as indicated in Figure 6. A centrally summated spaced mast system produces a figure-of-eight reception pattern having its null position perpendicular to the plane of the masts.

Figure 8 illustrates the summation of the signals from masts 50 and 51 at the base of one of the antennae. The reception pattern with summation at the left antenna is shown in Figure 9 as a cardioid with its null position pointing toward the right and lying in the plane of the masts.

35 Figure 10 illustrates the summation of the two mast signals at the base of the right antenna 51 producing the cardioid reception pattern illustrated in Figure 11 having its null position pointing toward the left in the plane of the masts 50 and 51. The reason for the null reception pattern produced by the antenna array of Figure 10, for example, is that the time-phase lag between the signals induced in the vertical mast 50 reaches the primary 60 of the antenna transformer 61 in exact time-phase with the incidence of the signals upon the mast 51. Since the signals from the antennae 50 and 51 are introduced 180° apart at the primary winding 60, the effects of signals in the plane of the antennae 50-51 coming from the left are nullified to produce the null shown in Figure 11. Signals originating from the right are impressed upon antenna 51 first and the time-phase displacement between the signals impressed upon the antenna 50 is twice that corresponding to the spacing between the antennae 50 and 51 since it takes approximately equal time intervals for the radiant energy to traverse the space between the antenna 50 and 51 as it takes for the electrical signals to travel across the conductor 56 between the second impressed antenna 50 and the primary winding 60.

65 In Figures 12 and 14 are illustrated an antenna system and circuits having the antenna transformer 61 located centrally between the masts 50 and 51 and employing a time-delay network 58 to produce a resultant cardioid reception pattern. By placing the time-delay network 58 in the connection lead 57 from the right hand antenna 51, the cardioid reception pattern illustrated in Figure 13 is produced with its null position toward the right corresponding to Figures 8 and 9. By placing the time-delay network 58 in circuit with the lead 56 from the left antenna 70 50, the left hand cardioid pattern of Figure 15

is produced. The time-delay network 58 is designed to superimpose a time-phase displacement upon the antenna signal conducted to the primary 60 of the transformer 61 equivalent to the distance between the spaced antenna 50 and 51, namely the time consumed by the travel of the radiant energy between the two masts. With such a time-delay, the signals impressed from both ends upon the primary 60 will be substantially equal and of opposite phase to produce the null as indicated by the illustrated reception patterns.

In Figure 16 I have illustrated the double mast right-left indicating direction finding system employing the alternately switched time-delay network 58 with switching circuits 64 to 67 corresponding to the system of Figure 5. In place of the simple vertical masts 50 and 51 I herein employ doublet antenna systems 50' and 51' coupled to the connection leads 56 and 57 through coupling transformers 70 and 71. The dipole antennae systems 50' and 51' are individually non-directional in character and are particularly useful for ultra-high frequency reception. By combining them with the time-delay network to produce the alternate cardioid reception patterns in a manner to be described, an efficient high frequency right-left indicating direction finder system is feasible.

Although the dipole antenna structures 50' and 51' may be mounted upon a vehicle in a stationary position, they may be rotatably mounted thereon in a manner described in connection with my co-pending application Serial No. 139,142, filed April 27, 1937, as particularly illustrated therein in Figure 4. Thus the null position of such direction finder is adjustable by the operator.

The switches 64, 65, 66 and 67 are alternately switched between their contacts from the solid position illustrated to the opposite position. The alternate switching of these switches connects the time-delay network 58 alternately in series between the antenna connection leads 56 and 57 and the primary 60 of the transformer 61. The illustrated connections of the switches 64 to 67 connect the time-delay network 58 into the connection lead 56 corresponding to the left antenna system 50' to produce the left cardioid reception pattern 72 of Figure 17. Curve 72 corresponds to the cardioid produced by the system of Figure 14. The alternate position of the switches 64 to 67 connects the time-delay network 58 into the connection lead 57 producing the right cardioid reception pattern 73 shown in dotted lines in Figure 17 corresponding to that produced by the system of Figure 12. Continuous alternate switching of the time-delay network into the left and right antenna connections correspondingly successively produces the left and right cardioid polar reception patterns 72 and 73.

The successive right and left cardioid reception patterns introduce a signal upon the input of radio receiver 63 of magnitude corresponding to the angle incidence θ of the radio waves with respect to the plane of the antenna system. In Figure 17, the angle θ was shown to intercept the right and left cardioids to produce different relative magnitudes of input for a predetermined signal. As shown in Figure 5, the output of the radio receiver is correspondingly switched to the right and left sections of the differentially indicating meter 68 where the effects of the two types of polar reception patterns are algebraically summated to produce a resultant indication of

the needle to the right or left in accordance with the respective intensities of the reception patterns.

In carrying out my present invention, I generate cardioid reception patterns solely dependent upon the geometric position of the antenna array used. By using the time-delay network 58 which is substantially independent of the signal frequencies used, a definite time-lag or phase displacement is introduced upon all signals passing therethrough. The phase displacement is made to correspond to the actual spacing of the antennae so that all resultant signals introduced to the radio receiver 63 will have a cardioid polar reception pattern.

In Figures 18 to 22, I have illustrated different forms for the time-delay network 58. In Figure 18, a distributed inductance 74 and 75 interconnected by a series of capacitances 76 produces an electrical long line or time-delay network between the input terminals 77 and output terminals 78. The characteristic impedance Z_0 of such network is preferably designed equal to the impedance of the individual antennae and the coupling transformers in order to eliminate interference and reflections as well known in the electrical art. The time-delay network is designed along well known theory to be substantially distortionless and independent of frequency discrimination. At the high frequencies used, the attenuation constant is readily made substantially negligible. The velocity propagation of the radio frequency currents through the network determines the time-phase displacement between the input and output terminals 77-78. Figure 19 illustrates an alternative long line or time-delay network composed of one inductance section 80 and a series of capacitances 81. Such a half-section line is preferably used where one side is connected to ground as illustrated.

Figures 20 and 21 illustrate time-delay networks composed of lumped inductive and capacitive elements 82 and 83 forming balanced and half-section time-delay networks corresponding to Figures 18 and 19 respectively. By using proper design constants for the respective inductances 82 and capacitances 83, a distortionless long line substantially independent of frequency and actuation characteristics can be designed for the frequency bands used for directional reception.

Figure 22 is a continuous long line formed of a conductor 84 centrally positioned within a shielded housing 85. The distributed capacitance, inductance, resistance and conductance of the transmission line 84-85 are proportioned to have the distortionless properties to form the time-delay network 58. By designing the long line 84-85 into a flexible construction, it may be arranged into a form requiring a minimum of space.

Figure 23 illustrates the time-delay network corresponding to Figure 21 and having lumped inductance elements 82 and capacitance 83 connected in circuit as the time-delay network 58 of my right-left indicator system corresponding to Figures 5 and 16. The terminals 86-87 are connected to ground potential. The terminals 88 and 89 connecting to the inductances 82 are respectively connected to the switches 64 and 65. Signals impressed upon the antennae 50 and 51 are successively delayed by the network 58 to create a phase displacement necessary to form the alternate right and left cardioid reception

patterns as described in connection with Figure 17.

The time-delay network may be avoided where further antenna systems are not objectionable with respect to wind resistance, space, cost and the like. When it is realized that a mast antenna even when streamlined offers a minimum aerodynamic resistance to flight of an airplane traveling at 200 miles per hour, the time-delay network hereinabove described is useful for producing a direction finder system with a minimum number of antennae masts. In Figure 24 is illustrated a right-left direction finder system using cardioid reception patterns produced by four vertical antenna arrays 90 and 91, 92 and 93 and without using time-delay networks. The left antenna system 90-91 is summated by primary winding 94 at the base of antenna 91, corresponding to the system described in connection with Figure 10 and produces a left hand cardioid reception pattern corresponding to Figure 11. The right antenna array 92-93 is summated by primary winding 95 at the base of antenna 92 corresponding to the system described in connection with Figure 8 and producing a right hand cardioid reception pattern corresponding to Figure 9. The secondary windings 96 and 97 of the two antenna arrays are successively introduced to the input of radio receiver 63 by the switch 98. The output of receiver 63 is alternately introduced to the right and left sections of the differential indicating meter 68 by switch 69 in the manner described in connection with Figure 5.

The cardioids produced by the antenna arrays 90-91 and 92-93 do not depend on a time-delay network, correspondingly simplifying the switching system and circuits for producing the alternate right and left cardioid reception patterns. The reception patterns depend solely on the geometric arrangement of the antenna array and the angular position of the station and accordingly are not affected by the tuning or temperature variations or electrical parameter changes of the system. By rectifying the output of the radio receiver 63 to the extent of producing uni-directional current a sensitive direct current differential meter 68 may be used to summate the effects of the alternate antenna signal outputs to produce the corresponding right or left indications when the station is off null. The on-course null or 0 positions for this system of alternate right and left indications is perpendicular to the plane of the antenna array corresponding to the arrow shown in Figure 17, the position where signals to the right or left will cause deflections of the indicator 68 by signals from that direction producing balanced or null indications. Although I have illustrated mechanical switching arrangement to simplify the theoretical discussion and disclosures of my present invention I prefer to employ electronic switching arrangements whereby the transients in the radio frequency networks and circuits are eliminated. Such electronic switch systems are well known in the art and are hereinafter described in connection with the double and triple mast system but may be equally well employed with the four mast system of Figure 24.

In Figure 25 is illustrated a vertical mast, cardioid reception pattern, right left indicating direction finder system employing the principles of my present invention and utilizing three vertical masts to produce the cardioids without time-delay networks. The vertical masts or antenna arrays 100, 101 and 102 are combined to alter-

nately produce the right and left cardioid patterns of Figure 17. The central mast 101 is used in place of the two central masts 91 and 92 of Figure 24 and is alternately switched to the primary windings 94 and 95 connecting the left and right antenna masts 100 and 102 by switch 103. The secondary windings 96 and 97 are correspondingly connected to the input of radio receiver 63 by synchronous operation of the switch 98.

Figure 26 is a schematic diagram of a right-left indicator system similar to that of Figure 25. Three vertical masts 100, 101 and 102 are combined by means of electronic switching in a manner similar to the mechanical switching example of Figure 25. Two diode rectifiers 105 and 106 are employed with circuit connections for electronically combining the signals of the antenna masts to successively form right and left cardioid reception patterns at the input of radio receiver 63. The electronic switching frequency is preferably an audio frequency of the order of one hundred and forty cycles per second. The output of the radio receiver is electronically switched in synchronism with the antenna system by means of a third diode rectifier 107.

An audio frequency oscillator 108 comprising the triode 109 generates a current of frequency of the order of one hundred forty cycles. An iron core transformer 110 contains coils 111 and 112 coupled to the grid and plate respectively of the triode 109. Secondary windings 113, 114 and 115 are wound on the transformer 110 to transmit the audio frequency generated at the transformer to the electronic rectifier tubes 105, 106 and 107. The elements *a* of the rectifier tubes 105 and 106 are connected to the terminal 116 of the winding 113 through individual radio frequency choke coils 117 and 118. The *b* ends of the rectifiers 105 and 106 are connected to the opposite terminal 119 of the winding 113 to individual radio frequency choke coils 120 and 121.

The opposite terminals 116 and 119 of the secondary winding 113 are 180° out of phase with respect to each other and accordingly alternately render the *a* anodes and the *b* anodes conductive with respect to the cathodes of the rectifiers 105 and 106 in a manner familiar to those skilled in the art. I prefer to connect the cathode 122 of rectifier 105 to the neutral or midpoint 123 of winding 113 through the radio frequency choke coil 124. It is to be understood that the electronic switching circuit is herewith presented schematically and specific biasing conditions of the cathode are omitted for simplicity but are understood by those skilled in the art. The function of the diode rectifiers 105 and 106 is similar to the operation of the mechanical switches 103 and 98 of Figure 25 where mechanical switching is employed. In this example, however, the alternate conductive nature of the *a* anodes and the *b* anodes correspond to the alternate position of the switches 98 and 103 from the solid to the dotted position.

When the *a* anodes are conductive with respect to their cathodes, the signals from masts 100 and 101 combine through the primary winding 94 and induce a cardioid pattern in the secondary winding 96 which is conducted through the cathode 125 of rectifier 106 to the input of the radio receiver. The *b* anodes are nonconductive at this period and accordingly signals from mast 102 and transformer 95-97 are ineffective. Conversely, when the *b* anodes are conductive, the reversed cardioid pattern from

masts 101—102 combine at transformer 95—97 and actuate the input of radio receiver 63. The output of the radio receiver receiving the successive cardioid input voltages is synchronously switched between the left and right sections of the differential indicator 68 through the rectifier 107. The *a* anode of rectifier 107 is connected to the right hand terminal 126 of winding 115; the *b* anode, to the left hand terminal of winding 114. The terminals 126 and 127 are maintained at similar alternating current voltage potential and 180° out of phase in order to render the *a* and *b* anodes of diode 107 alternately conductive and in synchronism of the *a* and *b* anodes of the antenna diodes 105 and 106. The alternate conductive nature of the *a* and *b* anodes of diode 107 permits the rectified cardioid pattern outputs from radio receiver 63 to flow through the differential meter 68 in a predetermined manner to produce an indication to the right or left in accordance with the position of the radio transmitter as will now be evident.

Although I prefer to illustrate the triple mast example with electronic switching, I do not wish to be limited thereto since the established principles of electronic switching may be employed in the four mast case corresponding to Figure 24 as well as to the two mast case of Figures 5, 16 and 23 employing the time delay network 58. The electronic switching renders the diode anodes successively conductive with respect to the common cathode and permits the conduction of the radio frequency currents at the antenna stage to be combined in a predetermined manner similar to the simplified showing with the mechanical switching illustrations.

Although I have illustrated preferred forms for carrying out my present invention, it is to be understood that modifications are feasible and I do not intend to be limited except as set forth in the following claims.

I claim:

1. A radio direction finder system comprising a first non-directional antenna; a second non-directional antenna; means for combining the signal outputs of said first and second antennae to successively form differently oriented polar cardioid reception patterns; an indicator; and means for producing right-left indications on said indicator in accordance with the relative position of the antennae with respect to the signal source.

2. A radio direction finder system comprising a first non-directional antenna; a second non-directional antenna; means for combining the signal outputs of said first and second antennae and means for alternately delaying the outputs of said antennae with respect to each other to successively form differently oriented polar cardioid reception patterns, comprising a time delay network in circuit with said antennae; an indicator; and means for producing right-left indications on said indicator in accordance with the relative position of the antennae with respect to the signal source.

3. A radio direction finder system comprising a first non-directional antenna; a second non-directional antenna; and means for combining the signal outputs of said first and second antennae to successively form differently oriented polar cardioid reception patterns, a time delay network and switching means for alternately connecting said network in circuit with said first and second antennae.

4. A radio direction finder system comprising

a first vertical mast antenna; a second vertical mast antenna; a radio receiver responsive to said antenna signals; an indicator connected to the output of said receiver; means for alternately combining the signal outputs of said first and second antennae to successively form differently oriented polar cardioid reception patterns and switching means for alternately connecting a time delay network in circuit with said first and second antennae; and means for correspondingly switching the output of said receiver at said indicator for producing right and left deflections in accordance with the direction of the signal transmitter with respect to the position of said antennae.

5. A radio direction finder system comprising a first vertical mast antenna; a second vertical mast antenna; a radio receiver responsive to said antenna signals; a differential indicating meter connected to the output of said receiver; and means for alternately combining the signal outputs of said first and second antennae and means for alternately delaying the outputs of said antennae with respect to each other to successively form right and left oriented polar cardioid reception patterns comprising a time delay network.

6. A radio direction finder system comprising a first non-directional antenna; a second non-directional antenna; a radio receiver responsive to said antenna signals; a differential indicating meter connected to the output of said receiver; means for combining the signal outputs of said first and second antennae to successively form right and left oriented polar cardioid reception patterns comprising a time delay network and switching means for alternately connecting said network in circuit with said first and second antennae; and means for correspondingly switching the output of said receiver at said differential meter for producing right and left deflections in accordance with the direction of the signal transmitter with respect to the position of said antennae.

7. A radio direction finder system comprising a first non-directional antenna; a second non-directional antenna; a radio receiver responsive to said antenna signals; an indicator connected to the output of said receiver; means for combining the signal outputs of said first and second antennae to successively form differently oriented polar cardioid reception patterns comprising a time delay network and switching means for alternately connecting said network in circuit with said first and second antennae; and means for correspondingly switching the output of said receiver at said indicator for producing right and left deflections in accordance with the direction of the signal transmitter with respect to the position of said antennae.

8. In a right-left indicating direction finding system, a plurality of non-directional antennae; circuit connections extending from said antennae for combining the signals from said antennae to produce non-symmetrical polar patterns; an indicator connected to said circuit connections; and means whereby said indicator is alternately controlled by signals forming said patterns to produce right-left indications in accordance with the relative position of the antennae with respect to the signal source.

9. In a right-left indicating direction finding system, a plurality of non-directional antennae in spaced relation; means for combining the signals intercepted by said antennae to produce

alternate reversed non-symmetrical polar patterns; an indicator and means for alternately applying the signals forming each of said patterns to said indicator; and means whereby said indicator operates in response to said signals for producing right-left indications in accordance with the relative position of the antennae with respect to the signal source.

10. In a right-left indicating direction finding system, a plurality of non-directional antennae in spaced relation; means for combining the signals intercepted by said antennae to produce alternate reversed non-symmetrical polar patterns; an indicator and means for alternately applying the signals forming each of said patterns to said indicator; and means whereby said indicator operates in response to said signals for producing right-left indications in accordance with the relative position of the antennae with respect to the signal source and in accordance with the sense of said signals.

11. In a right-left indicating direction finding system; a plurality of antennae in predetermined spaced relation; a time delay network having a time delay characteristic in accordance with the spatial relation of said antennae; an indicator; circuit connections to said indicator; and switching means for interposing said time delay network between said circuit connections and each of said antennae successively and for simultaneously connecting the other of said antennae in circuit with said circuit connections.

12. In a right-left indicating direction finding system; a plurality of antennae in predetermined spaced relation; a time delay network having a time delay characteristic in accordance with the spatial relation of said antennae; said network being connected in series with said antennae; an indicator; circuit connections from said indicator to said antennae circuit; and switching means for successively switching said time delay network between each of said antennae and said circuit connections.

13. In a right-left indicating direction finding system; a plurality of antennae in predetermined spaced relation; a time delay network having a time delay characteristic in accordance with the spatial relation of said antennae; said network being connected in series with said an-

tennae; an indicator; circuit connections from said indicator to said antennae circuit; switching means for successively switching said time delay network between each of said antennae and said circuit connections; and switching means for correspondingly successively reversing said indicator with respect to said circuit connections.

14. In a right-left indicating direction finding system; a plurality of antennae in predetermined spaced relation; a time delay network having a time delay characteristic in accordance with the spatial relation of said antennae; said network being connected in series with said antennae; a translating means connected in said series circuit; and switching means for switching said time delay network between each of said antennae and said translating means successively for producing a plurality of non-symmetrical polar patterns.

15. In a right-left indicating direction finding system; a plurality of antennae in predetermined spaced relation; a time delay network having a time delay characteristic in accordance with the spatial relation of said antennae; said network being connected in series with said antennae; a translating means connected in said series circuit; switching means for switching said time delay network between each of said antennae and said translating means successively for producing a plurality of non-symmetrical polar patterns; an indicator; circuit connections from said indicator to said translating means; and means whereby said indicator operates to indicate the relative position of the antennae with respect to the signal source.

16. In a right-left indicating direction finding system; a plurality of non-directional antennae in spaced relation; an indicator; means for producing cardioid patterns by means of said antennae in accordance with the orientation thereof; switching means for reversing said patterns; means for alternately impressing said signals on said indicator to indicate to the right or left of the direction of the incident signal, depending upon the angular position of the plane of the antennae with respect to the signal source.

EDWARD J. HEFELE.
